(57) **CLAIM**

The ornamental design for portable terminal, as shown and described.

DESCRIPTION

FIG. 1 is a front perspective view of a portable terminal showing my new design;

FIG. 2 is a front view thereof;

FIG. 3 is a rear view thereof;

FIG. 4 is a right side view thereof;

FIG. 5 is a left side view thereof;

FIG. 6 is a top plan view thereof;

FIG. 7 is a bottom view thereof;

FIG. 8 is a front view in an opened state thereof;

FIG. 9 is a rear view in the opened state thereof;

FIG. 10 is a top plan view in the opened state thereof; and,

FIG. 11 is a front perspective view in the opened state thereof.

The evenly-spaced short dashed lines shown on FIGS. 3 and 9 are for the purpose of illustrating unclaimed portions of the portable terminal and form no part of the claimed design.
